Primary Examiner—Susan J. Lucas*Assistant Examiner*—Holly Baynham*Attorney, Agent, or Firm*—Hill, Steadman & Simpson[57] **CLAIM**

The ornamental design for swivel hook, as shown.

DESCRIPTION

FIG. 1 is a front view of a swivel hook;

FIG. 2 is a rear view of the swivel hook of FIG. 1;

FIG. 3 is a plan view of the swivel hook of FIG. 1;

FIG. 4 is a base view of the swivel hook of FIG. 1;

FIG. 5 is a right side view of the swivel hook of FIG. 1;

FIG. 6 is a cross-sectional view taken on line 6—6 of FIG. 1;

FIG. 7 is a cross-sectional view taken on line 7—7 of FIG. 5; and,

FIG. 8 is an explanatory view showing the swivel hook of FIG. 1 in use.

The broken line showing of strap material and swivel hook structure is for illustrative use only and forms no part of the claimed design.

FIG. 1

FIG. 2
